(57) **CLAIM**

The ornamental design for a water pump, as shown and described.

DESCRIPTION

FIG. 1 is a front elevation view of a water pump showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is another perspective view thereof.

FIG. 9 is a perspective view of the water pump attached to a nozzle.

The broken lines of FIG. 9 depicting a nozzle represent environmental structure that forms no part of the claimed design. The remainder of the broken lines depict portions of the water pump that form no part of the claimed design.
